FRANK E. HEATH, OF NEW YORK, N. Y.

DESIGN FOR A HANDKERCHIEF, &c.

SPECIFICATION forming part of Design No. 25,595, dated June 2, 1896.

Application filed April 17, 1896. Serial No. 588,047. Term of patent 7 years.

To all whom it may concern:

Be it known that I, FRANK E. HEATH, a citizen of the United States, residing at New York, in the county of New York and State of New York, have invented and produced a certain new and original Design for Handkerchiefs, Rugs, Carpets, and Similar Goods, of which the following is a full, clear, and exact description.

10 In the accompanying drawings the figure is a plan view of a handkerchief or similar article, showing my design applied diagonally thereto.

The design in general consists of a handkerchief or similar article having upon it a more or less idealized figure of the tree known as the "royal palm," the essential feature being a palm-tree having a smooth light-colored trunk extended at the top by a short 20 section of darker color.

The design consists in representing the trunk of the tree as a straight smooth round column a, light in shade, with cross-stripes of a lighter shade, and set against a comparatively dark background. The column is topped or extended by a section b of less diameter and having a symmetrical shape similar to that of an Indian club, though with less difference between the greatest and least diameters and having less pronounced curves. 30 This extension is of a contrasting darker shade than the main trunk or column and from it springs the foliage of the tree. The foliage c, as shown, consists of seven branches or spiked leaves bending in upward and outward curves from the upper extremity of the section b. The main trunk a is shown as springing through a mass of foliage d of similar character to that of the tree itself.

The design also includes a representation 40 of several birds; but these and the foliage d at the base of the trunk are non-essential features of the design.

The general effect of the whole figure presented to the eye is that of a palm-tree having a long smooth light-colored trunk extended at the top by a short section of a darker color or shade, and this is the essential feature of my design. 45

I claim—

The design for handkerchiefs or similar articles, as herein shown and described.

In testimony whereof I subscribe my signature in presence of two witnesses.

FRANK E. HEATH.
